UNITED STATES PATENT OFFICE.

FINIS E. ROACH, OF CHICAGO, ILLINOIS.

SPRINKLER APPARATUS.

Application filed January 3, 1922. Serial No. 526,473.

To all whom it may concern:

Be it known that I, FINIS E. ROACH, a citizen of the United States, and resident of Chicago, in the county of Cook and State of Illinois, have invented a certain new and useful Improvement in Sprinkler Apparatus, of which the following is a full, clear, concise, and exact description, reference being had to the accompanying drawings forming a part of this specification.

This invention relates to sprinkling apparatus, and particularly to that type in which the nozzle is given a slow rotary motion in order that the sprinkling device may distribute the water to a comparatively large area, and in which automatically operating means are provided for shutting off the flow of water to the nozzle and stopping the rotation of the device at the end of any predetermined amount of rotation of the nozzle.

One of the features of the invention is the provision of an automatically operated valve timing device which is actuated solely by the water flowing through the sprinkler apparatus, and which is capable of being set so as to shut off the water at the end of a desired number of revolutions or at the end of any desired fraction of a revolution of the nozzle.

Another feature of the invention is the arrangement of the cut-off valve in the discharge pipe to the nozzle, which upon closure, acts to definitely stop the flow of water from the nozzle and incidentally stops the rotation of the nozzle.

Another feature is the provision of an improved structure which permits the cut-off valve to be actuated, due to the pressure of water in the apparatus.

Other features and advantages of the invention will appear as the description of the device progresses.

In the drawings which illustrate one form of the device:

Figure 1 is a side elevation of the outside of the complete sprinkler device;

Figure 2 is a sectional view on the line 2-2 of Figure 1, looking upwardly;

Figure 3 is a cross sectional view on the line 3-3 of Figure 2;

Figure 4 is a vertical section showing the structure of the shut-off valve;

Figure 5 is a cross section on the line 5-5 of Figure 4, looking in the direction of the arrows;

Figure 6 is a section on the line 6-6 of Figure 3; and

Figure 7 is a section on the line 7-7 of Figure 3.

Similar reference characters refer to similar parts throughout the several views.

Before giving a detail description of the device, a general description of the operation of the arrangement will be given. The water under pressure enters the base of the sprinkler receptacle and acts on a spider or star wheel to cause rotation of the star wheel. The sprinkler base and receptacle are stationary in the sense that they do not move during the sprinkling operation in any one area although the sprinkler may be moved to sprinkle different areas as desired. This operation is quite similar to the operation of the usual water turbine. Carried by the star wheel is a shaft provided with a worm gear which operates through reducing mechanism to cause a slow rotation of the portion of the sprinkler upon which the nozzle and related parts are mounted. The timing element of the nozzle is set by the operator grasping the nozzle and depressing it and then rotating it a fraction of a revolution, or a plurality of revolutions, as desired, thus causing a fixed lug to travel around in the threads of the timing device.

Between the timing device which carries the nozzle and the gear mechanism previously referred to, there is a friction engagement which permits the longitudinal and rotary movement of the timing device, but which normally causes the timing device and nozzle to rotate with the last element of the reducing train of gearing. Now assuming that the timing device has been set as above explained, and water is flowing through the sprinkler, a gradual rotary motion of the timing device and valve of the nozzle will take place. When this timing device and the nozzle thereon have rotated a sufficient distance to cause the fixed lug to travel back to the end of the spiral groove or thread in which it was moved during the setting operation, the timing device and the shut-off valve carried thereby will be released and

the water pressure within the sprinkler receptacle will cause the valve to seat and thus cut off the water from the sprinkler nozzle.

Referring now to the drawings, 10 indicates the bottom of the stationary basin-like sprinkler receptacle, which is provided about its outer circumference with the up-

standing annular flange 11. Integral with the flange 11 at one side thereof is the inlet nipple 12 provided with the passage-way 13 which opens at an angle into the interior of the sprinkler receptacle. The nipple 12 is provided with internal threads 14 to permit the attachment thereto of the usual hose coupling.

The bottom 10 of the receptacle is provided at its central portion with the screw-threaded opening 15 within which is screwed the cap bearing member 16. Secured to the flange 11 at the upper edge thereof, as by means of the screws 17, is the cover plate 18. The plate 18 is a flat circular plate provided on one side thereof with the raised housing 19, which preferably is integral with the remainder of the cover plate 18. Formed in the upper wall of the housing 19, and directly opposite the opening 15 in the plate 10 is a screw-threaded opening 20 within which is screwed the cap bearing 21. Shaft 22 has its opposite ends received in the bearings 16 and 20, respectively, and adjacent its lower end is provided with the screw-threaded portion 23, which is received by a screw-threaded recess 24 within the hub 25 of the turbine spider 26 having the projecting flanges or vanes 27. It is to be understood that the hub 25 is non-rotatably fixed to shaft 22.

Formed on the shaft 22, adjacent to the end remote from the turbine spider 26, is the worm 27. The housing 19 is provided in its opposite side walls with the cap bearings 28 and 29 which receive the opposite ends respectively of the shaft 30. Rigidly secured to the shaft 30, as by means of the nuts 31 and 32 screw-threaded on the shaft, is the worm gear 33 which is arranged to mesh with the worm 27 on the shaft 22. The shaft 30 at its end remote from the worm gear 33 is provided with a worm 34.

The housing 19 is provided in its upper surface, as seen in Figure 3, with a cylinder-like member 36. Spaced from the outer portion of the lower end of the cylinder-like member 36 is the sleeve 37. Sleeve 37 is provided at its upper edge with the inwardly extending flange 38, arranged between the end of the collar 39 which is screw-threaded on the member 36, and the inner surface of the upper portion of the housing 19. Thus the sleeve 37 is rotatable about the member 36, but is prevented from longitudinal movement by its flange 38.

Integral with the sleeve 37 and extending outwardly therefrom is the worm gear 40 which is arranged to mesh with the worm 34 on the shaft 30. Thus it will be seen that the water rushing into the sprinkler receptacle through the opening 13 will cause the turbine spider 26 to revolve, and, through the train of gearing, including shaft 22, worm 27, worm wheel 33, shaft 30, worm

34 and worm gear 40, the collar will be caused to slowly rotate about the member 36.

Rigidly secured to the collar 37, and preferably integral therewith, is a plurality of 70 downwardly extending spring fingers 41. The collar 39 is provided at its lower end with the inturned flange 42. The flange 42 and the end of the member 36 form a space within which is positioned the packing ring 43 of felt or any other suitable material. Flange 42 acts to maintain the packing ring 43 in position, yet leaves the inner edge of the packing ring uncovered so that it may be directly engaged by the movable member of the shut-off valve.

Slidably and also rotatably arranged within the member 36 is the cylinder-like member 46. Member 46 is provided with an enlarged head 47 at the lower end thereof, which is secured to the cylinder 46 by means of the tie members 48 (see Figure 4). Thus it will be obvious that water under pressure in the sprinkler receptacle may pass through the openings between the spring fingers 41, 90 then through the openings between the tie members 48 and into the opening through the center of the member 46.

The member 46, adjacent to its upper end, is provided with the screw threads 49, which are arranged to receive cooperating screw threads on the inlet branch 50 of a nozzle 52. The branch 50 communicates with an angularly extending member 52. The member 52 is provided with screw threads at 53, with which co-operates the screw-threaded portion 54 on the nozzle opening controlling member 55. The rear end of the member 55 is provided with a knurled hand-piece 56 by means of which the member 55 may be rotated to cause the enlarged portion 57 of the nozzle controlling member 55 to approach or recede from the nozzle opening 58. The member 52, at the rear of the screw-threaded portion 53, is formed with the recess 59, within which is positioned the coil spring 60. The nozzle controlling member 55 is provided with a shoulder 61 and the spring is arranged to be compressed between the shoulder 61 and the end of the recessed portion 59. The spring 60 acts to keep the screw-threaded portions 53 and 54 in firm engagement, and thus tends to prevent accidental displacement of the nozzle controlling member 55. As the screw-threaded portions are kept in firm engagement by the spring 60, the leakage of water between the members past the screw-threaded portions is also very much reduced.

The inlet portion 50 of the nozzle is provided on diametrically opposite sides with the lugs or bosses 62 and 63. An opening 64 is formed through the boss 62 and substantially through the boss 63, as by drilling.

The outer end of the boss 62 may then be plugged up in any desired manner. Slots 64' and 65 are then formed in the forward portions of the lugs 62 and 63, as by sawing. These slots 64' and 65 communicate with the opening 64, which, in turn, communicates with the opening through the inlet member 50. Thus the water under pressure in the sprinkler receptacle not only passes out through the space between the nozzle opening 58 and the adjusting member 57, but also a pair of fish tail sprays pass from the openings 64' and 65, respectively. This arrangement tends to insure that the spray from the nozzle will all be directed away from the sprinkler device. Thus the user can handle the sprayer with little danger of being wet. The member 46, when in a position to permit the water to pass to the nozzle, will be in the position, such as indicated in Figure 4,—that is, it will be in its lower position.

The automatic shut-off and timing means will now be described. The cylinder-like member 36 is provided with the inwardly extending lug 66. The member 46 is provided with the screw-threaded portion 67 and two slots 68 and 69, which are formed in the outer surface of the member 46 and communicate with the threaded portion 67. Thus, when the member 46 is inserted from below, as seen in Figure 3, into the member 36, the lug 66 may be caused to pass through the slot 68 to the screw-threaded portion 67. Then, by rotating the member 46, the lug 66 will pass around through the threads of the threaded portion 67 until the longitudinally extending slot 69 at the end of the last thread is reached. Then the member 46 may be moved upwardly into the position shown in Figure 3. In this position, the shoulder 70 will engage the packing ring 43 and close the opening through which water may pass to the spray nozzle. It will now be seen that if the nozzle is grasped by the operator and forced downwardly so as to cause the lug 66 to engage the screw-threaded portion 67, and the associated part is then rotated in a counter-clockwise direction, the lug 66 will enter the first thread of the screw-threaded portion 67 and the screw-threaded portion may be moved around over the lug until the lug is positioned any desired fraction or number of turns from the slot 69. As long as the lug 66 is in engagement with the screw-threaded portion 67, the member 46 will be maintained in its lowered position, such as shown in Figure 4, and water will be permitted to flow to the sprinkler nozzle.

The spring fingers 41, carried by the sleeve 37, are arranged to frictionally engage the enlarged portion 47 carried by the control member 46. The engagement between the fingers 41 and member 47 is such that 46 may be caused to move longitudi-

nally or in a rotary direction by the operator, but, when freed, will be caused to rotate with the sleeve 37. It will be remembered that the water rushing into the sprinkler receptacle through the opening 13, causes the rotation of the turbine spider 26, and this movement of the spider 26 through the medium of the reducing gearing previously referred to, causes a very slow clockwise movement of the sleeve 37. Due to the frictional engagement of the fingers 41 with the head 47 of the control member, the member 46, and the nozzle 51 mounted thereon, will be caused to move in the same manner and direction as the sleeve 37. As the nozzle and attached parts are rotated in a counter-clockwise direction in order to set the timing device,—that is, in order to cause engagement of the screw-threaded portion 67 with the lug 66, it is obvious that, when the nozzle is rotated in the clockwise direction, due to the passage of water through the sprinkler, it will be gradually returned to a position where the lug 66 will reach the end of the lowermost thread of the portion 67, and will be positioned in the longitudinally extending slot 69. As the water within the sprinkler receptacle is under pressure, and as the member 46 is free to move longitudinally, it is obvious that as soon as the lug 66 reaches the slot 69, the member 46 will be moved upwardly by the water pressure and the shoulder 70 will engage the packing ring 43, thus shutting off the water from the sprinkler nozzle. As the water can now no longer flow through the sprinkler receptacle, the rotation of the turbine spider 26 will stop and the device will remain in an inactive condition until again set by the operator.

Even when the sprinkler device is operating in its intended manner, as explained above, the rotary movement of the nozzle is so extremely slow, due to the reducing train of gearing between the spider 26 and the collar 37, that an observer would find it difficult to detect any rotary movement of the nozzle. Therefore, in order that one may readily determine that the timing device is operating properly, a pointer or finger 71 is provided. The cap bearing 29 for one end of the shaft 30 is provided with a central opening and the shaft 30 is provided at its adjacent end with a longitudinally extending screw-threaded opening. The finger 71 is secured to the shaft 30, so as to rotate therewith by inserting the screw 72 which is secured to the pointer 71 through the opening in the bearing cap 29 and securing it firmly into the screw-threaded opening in the shaft 30. Thus, by observing the finger 71, which will rotate at a much more rapid rate than the sprinkler nozzle, the user may readily determine if the timing device is functioning.

- It is evident that by means of the structure above described, the sprinkler may be set so as to spray any desired sector of a lawn or other surface. Or, if it is desired to give the surface a thorough wetting, the device may be maintained in operation until the sprinkler nozzle has completed a desired number of rotations. When, however, due to the rotary movement of the nozzle under the influence of the flowing water, the lug 66 enters the slot 69, the pressure of the water will move the member 46 upwardly and immediately shut off the water from the sprinkler nozzle.
- 15 While, in the drawings, but a single embodiment of the invention has been disclosed, it is to be understood that modifications of the present embodiment are contemplated. The train of gearing, for instance, 20 may be changed so as to change the ratio of speed between the nozzle and the spider, and, in fact, the entire character of the reducing gearing may readily be altered. The member 46 may be provided with a greater or 25 less number of threads in the timing device and various modifications in the details of the shut-off valve and associated parts will readily suggest themselves to any mechanic. It is, therefore, to be understood that the 30 invention is to be limited merely by the scope of the appended claims.
- What I claim is:
1. In a sprinkler apparatus, a stationary receptacle, a source of water under pressure connected to said receptacle, a discharge nozzle connected to said receptacle to permit the discharge of water therefrom, a water motor within said receptacle arranged to be operated by water passing therethrough, means located in said stationary receptacle and operated by said motor for rotating said nozzle, a valve for cutting off the flow of water to said nozzle, and means 45 automatically actuated by said motor for operating said valve after a predetermined degree of rotation of said discharge nozzle.
  2. In a sprinkler apparatus, a stationary receptacle, a source of water under pressure connected to said receptacle, a discharge nozzle, a water motor within said receptacle and arranged between said source of water and said discharge nozzle, a train of gearing in said stationary receptacle between said motor and said nozzle whereby 55 said nozzle is rotated through the gearing by said motor, a valve for cutting off the flow of water to said nozzle, and means actuated by said motor for operating said valve.
  3. In a sprinkler apparatus, a water motor, a rotatable sleeve, reducing gearing between said motor and said sleeve, a discharge nozzle, supporting means for said nozzle, and means carried by said sleeve and arranged to adjustably engage said support-

ing means whereby said nozzle is rotated by said motor.

4. In a sprinkler apparatus, a fixed collar, a sleeve rotatably mounted on said collar, a water motor, gearing between said motor and said sleeve, a discharge nozzle supporting member mounted within said fixed collar, means whereby said supporting member may be rotated by said sleeve, a discharge nozzle carried by said supporting member, and co-operating cut-off valve members on said collar and supporting member respectively.

5. In a sprinkler apparatus, a fixed collar, a sleeve rotatably mounted on said collar, a water motor, gearing between said motor and said sleeve, a discharge nozzle supporting member longitudinally and rotatably movable within said fixed collar, means whereby said supporting member may be rotated by said sleeve, a discharge nozzle carried by said supporting member, and co-operating cut-off valve members on said collar and supporting member respectively.

6. In a sprinkler apparatus, a rotatably mounted sleeve, a discharge nozzle, a support for said nozzle having an opening therethrough and communicating with said nozzle, said support being slidably and longitudinally movable within said sleeve, a head on said supporting member, members carried by said rotatable sleeve arranged to frictionally engage said head, co-operating valve members, one being relatively fixed and the other carried by said head, means for maintaining said valve members in separated position, and means actuated by the rotation of said sleeve for permitting said valve members to co-operate to shut off the flow of water to said discharge nozzle.

7. In a sprinkler apparatus, a fixed collar, a sleeve rotatably mounted on said collar, a discharge nozzle, a support for said nozzle having an opening therethrough and communicating with said nozzle, said support being slidably and longitudinally movable within said collar, a head on said supporting member, members carried by said rotatable sleeve arranged to frictionally engage said head, co-operating valve members on said collar and said head, means for maintaining said valve members in separated position, and means actuated by the rotation of said sleeve for permitting said valve members to co-operate to shut off the flow of water to said discharge nozzle.

8. In a sprinkler apparatus, a discharge nozzle, a support therefor, a fixed collar, a lug projecting from said collar, a circumferential groove in said support arranged to receive said lug, co-operating cut-off valve members on said collar and said support, means permitting the movement of said support to position said lug within said groove, means for automatically ro-

tating said nozzle, and means actuated incident to said lug being moved to a predetermined position within said slot for permitting said valve members to co-operate 5 to shut off the flow of water to said nozzle.

9. In a sprinkler apparatus, a spray nozzle, a support therefor, a fixed collar, a lug projecting inwardly from said collar, a spiral groove about said support, a slot in 10 said support communicating with said groove and arranged to receive said lug, co-operating cut-off valve members on said collar and said support, means permitting the movement of said support to position 15 said lug within said groove and for automatically rotating said nozzle, and means actuated incidental to said lug becoming positioned within said slot for permitting said valve members to co-operate to shut off 20 the flow of water to said nozzle.

10. In a sprinkler apparatus, a fixed collar, a sleeve about said collar, a nozzle support within said collar, co-operating valve members on said collar and said support, a 25 projection extending inwardly from said collar, a circumferential groove formed in said support, said support being arranged to permit its being rotated to place said projection in said groove whereby said valve members are maintained in separated position, 30 means for rotating said sleeve, and means carried by said sleeve frictionally engaging said support to cause a similar rotation of said support whereby said groove is caused 35 to become disengaged from said projection to permit said valve members to assume operative position.

11. In a sprinkler apparatus, a fixed collar, a nozzle support longitudinally and rotatably movable within said collar, co-operating valve members on said collar and support, means for maintaining said valve members in separated position, means for 40 rotating said support, and means actuated incident to such rotation for permitting the co-operative engagement of said valve members.

12. In a sprinkler apparatus, a fixed collar, a nozzle support longitudinally and rotatably movable within said collar, co-operating valve members on said collar and support, co-operating means on said collar and said support, respectively, for maintaining said valve members in separated position, means for rotating said support, and means actuated incident to such rotation for permitting the co-operative engagement of 45 said valve members.

13. In a sprinkler apparatus, a collar, a 50 nozzle support within said collar, co-op-

erating valve members on said collar and said support, said valve member on said support being arranged to be actuated by water pressure, a projection extending inwardly from said collar, a circumferential 65 groove in said support, means permitting the rotation of said support to position said projection within said groove whereby said valve members are maintained in separated position, and means for automatically rotating said support whereby said projections will pass out of said groove to permit said valve members to assume operative relation.

14. In a sprinkler apparatus, a nozzle, 75 means for supplying water under pressure to said nozzle, means for rotating said nozzle, a valve for shutting off the flow of water to said nozzle arranged to be closed by the pressure of water in the system, 80 means for holding said valve open, releasing means for said holding means carried by said nozzle, and adjustable means for determining the degree of rotation of said nozzle necessary to render said releasing 85 means effective.

15. In a sprinkler apparatus, a discharge nozzle, a water motor, means for supplying water under pressure to said nozzle and motor, reducing gearing between said motor and nozzle whereby said motor will cause a slow rotary movement of said nozzle, a valve for shutting off the flow of water in the system, means for holding said valve open, and means associated with 90 said nozzle and rotatable therewith for releasing said holding means.

16. In a sprinkler apparatus, a discharge nozzle, a water motor, means for supplying water under pressure to said nozzle, 100 and motor, reducing gearing between said motor and nozzle whereby said motor will cause a slow rotary movement of said nozzle, a valve for shutting off the flow of water to said nozzle arranged to be 105 closed by the pressure of water in the system, means for holding said valve open, means associated with said nozzle and rotatable in unison therewith for releasing said holding means, and adjustable means for determining the degree of rotation of said nozzle necessary to render said releasing means effective.

In witness whereof, I hereunto subscribe my name this 23rd day of December, 1921.

FINIS E. ROACH.
